(57) **CLAIM**

The ornamental design for a reading light, as shown and described.

DESCRIPTION

FIG. 1 is a top perspective view of a reading light showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of portion marked as "9" in FIG. 1;

FIG. 10 is an enlarged view of portion marked as "10" in FIG. 1;

FIG. 11 is an enlarged view of portion marked as "11" in FIG. 1;

FIG. 12 is an enlarged view of portion marked as "12" in FIG. 1;

FIG. 13 is an enlarged view of portion marked as "13" in FIG. 2;

FIG. 14 is an enlarged view of portion marked as "14" in FIG. 2;

FIG. 15 is an enlarged view of portion marked as "15" in FIG. 2;

FIG. 16 is an enlarged view of portion marked as "16" in FIG. 3;

FIG. 17 is an enlarged view of portion marked as "17" in FIG. 3;

FIG. 18 is an enlarged view of portion marked as "18" in FIG. 3;

FIG. 19 is an enlarged view of portion marked as "19" in FIG. 5;

FIG. 20 is an enlarged view of portion marked as "20" in FIG. 5;

(Continued)

FIG. 21 is an enlarged view of portion marked as “21” in FIG. 6;

FIG. 22 is an enlarged view of portion marked as “22” in FIG. 7;

FIG. 23 is an enlarged view of portion marked as “23” in FIG. 8; and,

FIG. 24 is an enlarged view of portion marked as “24” in FIG. 8.

The dash-dash broken lines in the figures depict portions of the reading light that form no part of the claimed design. The dot-dash-dot broken lines in the drawings depict boundaries of the enlargement that form no part of the claimed design.

1 Claim, 16 Drawing Sheets
